CLAIM

The ornamental design for a ornate wristband, as shown.

DESCRIPTION

FIG. 1 is a top plan view of the ornate wristband of the present invention;

FIG. 2 is a bottom plan view of the ornate wristband of FIG. 1;

FIG. 3 is a right side elevational view of the ornate wristband of FIG. 1;

FIG. 4 is a left side elevational view of the ornate wristband of FIG. 1;

FIG. 5 is a front elevational view of the ornate wristband of FIG. 1; and,

FIG. 6 is a back elevational view of the ornate wristband of FIG. 1.

The broken line showing of a logo patch, in FIG. 1, is for illustrative purposes only and forms no part of the claimed design.
